AIR CHANGER

Charles E. Young, Cincinnati, Ohio, assignor to
The Eagle-Picher Company, Cincinnati, Ohio,
a corporation of Ohio

Application January 14, 1947, Serial No. 721,924

10 Claims. (Cl. 98—43)

1 This invention relates to ventilating apparatus and is particularly directed to a power driven air changer of improved design for installation in the attic or basement of a residential building to induce a controlled flow of fresh air through the building. Operating as an induction blower, the ventilating unit draws air from the rooms into the attic or basement to be discharged into the atmosphere through the windows or ventilator openings.

This apparatus is adapted primarily to be utilized during the summer months to induce ventilation through the building by developing a slight pressure differential between the living quarters and the attic, basement or other unoccupied portion in which the air changer is located. Cool outside air is introduced into the desired rooms through the windows or other openings and is circulated to the blower and discharged, thus cooling the house. Being operated electrically, the unit is regulated by a control switch located at some convenient point in the house, to be controlled at will or automatically. The system provides efficient positive ventilation, and permits fresh air to be inducted into the rooms desired, while those rooms requiring no ventilation may be closed off.

Although designed primarily for summer use, the system may also be utilized during the winter months to induce fresh air into the building for installation wherever a large volume of air is to be moved quietly and at low pressure.

The principal objective of this invention has been to provide a centrifugal type blower which is of better operating efficiency than centrifugal blowers heretofore available but which, at the same time operates quietly so as to be adapted for residential usage adjacent sleeping quarters.

The invention briefly is based upon the discovery that these improvements in performance are obtained in a drum type blower having tandem sets of impeller blades in which one set is disposed slightly in angular relationship to the other set. In this manner, a more uniform air flow is produced which noticeably increases the efficiency of the unit and facilitates its operation without noise or flutter.

It has been a further object to provide a blower having vanes which are constructed and arranged to absorb vibration incident to air flow and thereby lower the noise level to produce substantially silent operation.

Further objects and advantages of the invention will be more fully disclosed in the drawings and in the following detailed description in which

2 a typical embodiment of the improved structure is illustrated.

In the drawings:

Figure 1 is a side view of an installed air changer unit partially broken away to more clearly disclose the several features of the invention.

Figure 2 is a top plan view of the unit with parts broken away to further illustrate the structure.

Figure 3 is an enlarged sectional view taken on line 3—3, Figure 1, illustrating the impeller drive shaft and bearings therefor.

Figure 4 is a fragmentary enlarged side view of a portion of the impeller wheel illustrating the angular relationship of one set of the vanes with respect to the other set.

Figure 5 is a face view of one of the impeller vanes as removed from the impeller wheel.

Figure 6 is a sectional view taken on line 6—6, Figure 5, disclosing the sound deadening construction of the vanes.

Figure 7 is a longitudinal sectional view taken on line 7—7, Figure 5, further illustrating the construction of the vane.

Figure 8 is an enlarged fragmentary sectional view showing details of the construction shown in Figure 7.

Referring to Figure 1 of the drawings, the blower unit comprises essentially a frame indicated generally at 10, an impeller unit 11, and an electrical drive motor 12 mounted on the frame. The impeller wheel 11 is keyed upon the lower end of a vertical shaft 13 sustained in bearings 14 which are mounted upon the frame 10. The upper end of the shaft 13 carries a pulley 15 which is driven from pulley 16 of the motor 12 by means of a V-belt 17.

Frame 10 preferably is fabricated from channel iron members and is in the form of an inverted U-shaped hanger having a pair of vertical limbs 18—18, and a pair of spaced horizontal cross members 19—19. The horizontal members 19—19 are spaced from each other a sufficient distance to properly stabilize the shaft 13 which is journaled in the bearings 14—14 carried by the cross members 19—19. Cross members 19—19 likewise provide a mount for the drive motor 12 which is disposed to one side of the impeller unit.

Vertical side members 18 of frame 10 are suitably secured to a base plate 21 preferably by bolting the lower ends of the members to the base plate and to the vertical flange 22 surrounding it. This permits the unit to be shipped in knock down

condition making handling and installation easier. As shown, base plate 21 may be mounted directly upon the joists 23 of the building, for which purpose the flooring may be removed or omitted. Alternatively, the unit may be mounted directly upon the floor in which case a suitable opening is formed through the flooring to provide an air intake into the funnel 25 which communicates through the ceiling 26 to the room below. In either installation the joists supporting the blower are preferably reinforced by framing the opening in an appropriate manner. For basement installations, the arrangement of the building permits, the unit may be mounted beneath the joists with the funnel 25 opening in to the floor above. For other installation conditions, the blower unit may be mounted vertically for discharge from a plenum chamber.

An inlet funnel 25 is provided at the entrance to the wheel, and the upper end of the funnel may be secured to the base plate 21 in any approved manner for example by a beaded joint, or as shown, by a flange 27 secured to the underside of the base plate by welding or riveting. The base plate 21 includes an opening 20 matching the upper end of the funnel for admitting air into the open lower end of impeller wheel 11. The lower end of the funnel 25 has a circumferential flange 32, similar to flange 27, forming a marginal band flush with the lower surface of the ceiling as indicated at 33. The lower end of the funnel opening into the ceiling preferably includes an ornamental grill 35 to conceal the opening and provide a neat and finished appearance.

As shown in Figures 1 and 3 the impeller unit 11 is suspended for rotation on a vertical axis by the drive shaft 13, shaft 13 being secured against vertical displacement by means of collars 36—36 respectively adjacent the upper and lower bearing blocks 14. These collars are secured to shaft 13 by means of set screws, screw threaded in the collars and engaged against shaft 13. Each bearing block 14 includes ball bearings 38 having an inner race 40 engaged on shaft 13 and an outer race 41 seated in a recess formed in the bearing blocks. The respective bearing blocks are secured to the cross members 19 by means of bolts 43 in screw threaded engagement in the bearing blocks or if desired the bolts may be extended through the flanges of the bearing blocks and nuts applied to the ends of the bolts. Pulley 15, which drives the impeller, includes a hub 45 non-rotatably secured to shaft 13 by means of key 46. The pulley hub is maintained in position on the end of shaft 13 preferably by a friction or pressed fit of the hub on the shaft.

The impeller drum 11 is carried upon the lower end of shaft 13 by means of a flanged sleeve 47 keyed as at 46 to shaft 13. Additionally a pressed fit may be provided for which purpose the end of shaft 13 and the base may be tapered slightly. In order properly to reinforce and stabilize the rotor with reference to the drive shaft 13, a concave or dished reinforcing plate 50 is utilized, this plate being of circular configuration, and having its outer periphery secured by welding or other means to the top closure plate 51 of the impeller. Plate 51 is secured to the upper end of sleeve 47 by means of bolts 52 through plate 51 and flange 53 of sleeve 47, and the reinforcing plate 50 is secured by a bolt 54 screwthreaded into the end of shaft 13 to engage a washer 55 which in turn bears against reinforcing plate 50. This arrangement prevents angular displacement or springing of rotor with respect to shaft 13.

and the opposite or lower end of the impeller therefore need not be supported.

The impeller unit 11 as shown in the drawings includes respective upper and lower sets of vanes 62 divided by an intermediate shroud ring 60, each set of vanes being provided with a pair of lateral end flanges 61. The flanges of the upper set of vanes are secured respectively to the closure plate 51 and the shroud ring 60, and those of the lower set are secured to the shroud ring and to the intake ring 58 at the bottom of the impeller. As viewed in Figure 2 the vanes 62 and 63 are tangent to a circle concentric to the axis of the impeller. It is to be noted that the lower set of vanes 62 is in horizontal alignment with the upper set 63, but that the lower set is disposed at an angle vertically with respect to the upper set.

An intake ring 58 is disposed immediately above the discharge end of funnel 25 to provide an opening 64 in alignment with the opening 20 of the base plate 21. Intake ring 58 is spaced slightly above the base plate 21 to clear with the plate 21 although the two members are sufficiently close to prevent any substantial inefficient passage of air between the ring and plate.

It will be noted that the opening defined by the shroud ring 60 is proportionately smaller than the opening defined by the lower intake ring 58. Experiment has indicated that the shroud ring 60 improves the air flow characteristics, improves performance and increases the capacity of the unit.

Figure 4 diagrammatically illustrates the angular displacement of vanes 62 with respect to vanes 63 as indicated by the angle "A" disposes the lower or forward edge of the vane in advance of its rearward edge relative to the direction of impeller rotation. The vanes 63 are preferably set at 90° to the plane of the shroud ring 60 and closure plate 51 is indicated by the angle "B." This relationship creates a differential air flow of the upper section of the impeller relative to the lower section. In the preferred embodiment, by way of example, the vanes of the lower set are set 3½° relative to the upper set based upon impeller velocity and displacement, although this angle may be varied according to the design of the impeller. The precise flow path is not known but the turbulence is reduced, a smooth and even air flow is produced and the efficiency of the blower is materially increased.

Each vane is formed of sheet metal and constitutes in effect, a sheet metal envelope enclosing a layer of sound deadening material such as felt, soft fibreboard or the like. For this purpose the vane is formed of two panels, one overlying the other, with the marginal edges of the panels overlapped to enclose the sound deadening layer therebetween.

As shown in Figure 5, the vane is made up of sheet metal panels 68 and 69. Panel 69 includes at opposite transverse edges, flanges 61—61 by means of which the vanes are secured to the circular plates of the impeller by riveting or spot welding. The adjacent longitudinal edges of plate 69 include flanges 72, which as shown in Figures 7 and 8 are formed to overlie the plate 68 on the opposite side of the vane. The opposite transverse edges of plate 68 include doubled-over or inturned flanges 73 which serve as spacers to hold the plates apart a sufficient distance to provide space for the sound-dampening members 75 therebetween.

In the preferred construction the vanes are formed from light gauge sheet metal, for example $\frac{1}{16}$ inch thick aluminum, the panels 15 being approximately $\frac{1}{8}$ of an inch thick. These thicknesses combined in assembly, provide a vane approximately $\frac{1}{8}$ of an inch overall in thickness. It has been found that this structure eliminates the tendency of the vanes to vibrate hum or flutter when acted upon by the air stream, thereby reducing substantially the noise level of the blower.

In operation, the directive effects of the inclined vanes or blades, combined with the centrifugal action of all vanes, causes the air to be discharged radially about the entire circumference of the impeller. The pressure thus established causes an air flow to be induced through the funnel 25 to the interior of the impeller, for circumferential discharge from the unit. From the attic the air is discharged into the atmosphere through suitable openings. As noted, the entry of air is controlled by adjusting the window openings in the building so that a desired amount of air is drawn into the building from the outside.

The motor 12 drives the impeller at a constant rate of speed. However, when the intake of air is reduced by closing the windows or other ventilating openings, the back pressure against the blower increases, or in other words the intake of air into the impeller is restricted. It is intrinsic in the design of the present structure that under this condition the motor load decreases with no appreciable increase in speed. Therefore the unit compensates automatically for abnormal conditions of operation to prevent over loads which might otherwise lead to damage or motor failure. Moreover the unit may be operated without over load control or speed change apparatus to compensate for changing conditions. The improved design further eliminates the necessity of providing a blower housing.

Having described my invention, I claim:

1. An air changer unit comprising, a frame, a rotary impeller disposed within said frame, said impeller having an end closure plate and an open opposite end forming an air intake, a series of vanes in said impeller, said vanes arranged in tandem sets, the vanes of one of the sets being disposed in alignment with the longitudinal axis of the impeller and the vanes of the other set being disposed at an angle to the longitudinal axis of the impeller.

2. An air changer unit comprising, a frame, a rotary impeller disposed within said frame, said impeller having an end closure plate on one end, the opposite end being open to form an air intake, a series of vanes in said impeller, each of said vanes being formed of a pair of metal plates having a layer of sound deadening material disposed therebetween to absorb vibrations caused by a flow of air relative to the vanes.

3. An air changer comprising, a frame, an impeller wheel disposed within said frame, a drive shaft for said impeller wheel, bearing means for said shaft mounted on said frame, an air intake duct, said impeller wheel having two sets of vanes, one set being disposed at an angle in plane longitudinally to the plane of the other set, said impeller wheel having an open end communicating with said intake duct to draw air through the duct and discharge the air radially about the circumference of the impeller.

4. An air changer unit comprising, a frame, a rotary impeller wheel disposed on a vertical axis within said frame, said impeller wheel having a

top closure plate and an open lower end forming an air intake, a series of vanes in said impeller wheel, said vanes arranged in tiers one above the other, the vanes of the upper of said tiers being disposed in alignment with the vertical axis of the impeller and the vanes of the lower tier being disposed at an angle to the vertical axis of the impeller with their forward edges in advance of their rearward edges relative to the direction of rotation.

5. An air changer unit comprising, a frame, a rotor disposed in a vertical axis, a rotor shaft having its lower end secured to said rotor and having its upper end journaled in said frame, said rotor including a top closure plate, an intermediate shroud ring and a lower intake ring, a series of vanes between said top plate and said intermediate plate and a second set of vanes between said intermediate plate and said lower intake ring, said second set of vanes being disposed in substantial alignment in a horizontal plane with said first mentioned set but being offset angularly in a vertical plane with respect to said first mentioned set of vanes.

6. An air changer unit adapted to be installed in an upper portion of a building to induce a flow of air through the building comprising, an inverted U-shaped frame, a mounting plate for said frame, said mounting plate adapted to be installed upon the floor of the building and including an air intake opening, an air intake duct connected to said opening, said duct opening into the area beneath said air changer, a rotor carried by said U-shaped frame, power means for driving the rotor, said rotor being disposed on a vertical axis and having an open lower end communicating with the air intake opening of said mounting plate and adapted to induce a flow of air from the area below, through said air intake duct into the rotor for discharge radially about the circumference of said rotor into the upper portion of the building.

7. An air changer unit comprising, a frame, an impeller rotatably mounted in said frame, power means for driving said impeller, said impeller having an air intake opening at one end thereof and having an intermediate shroud ring spaced inwardly from said intake opening, a closure plate spaced rearwardly from said shroud ring, said shroud ring providing an opening of smaller diameter than said air intake opening which constitutes a restricted passageway for the flow of air to distribute the discharge of air longitudinally along the impeller, said impeller having a set of vanes disposed between said intake opening and shroud ring, said vanes being disposed at an angle to the longitudinal axis of the impeller, and having a second set of vanes disposed between said shroud ring and closure plate, said second set being disposed in parallelism with the longitudinal axis of the impeller.

8. An air changer unit comprising, a frame, an impeller rotatably mounted in said frame, power means for driving said impeller, said impeller having an air intake opening at one end thereof and having an intermediate shroud ring spaced inwardly from said intake opening, a closure plate spaced rearwardly from said shroud ring, said shroud ring providing an opening of smaller diameter than said air intake opening which constitutes a restricted passageway for the flow of air to distribute the discharge of air longitudinally along the impeller, said impeller having a set of vanes disposed between said intake opening and shroud ring, said vanes being disposed at

an angle to the longitudinal axis of the impeller, and having a second set of vanes disposed between said shroud ring and closure plate, said second set of vanes being disposed in alignment with the longitudinal axis of the impeller.

9. A residential air changer unit comprising, a frame, a rotary impeller disposed within said frame, said impeller having an end closure plate and an open opposite end forming an air intake, a series of vanes in said impeller, said vanes arranged in tandem sets, the vanes of one of the sets being disposed at an angle in plane longitudinally to the plane of the vanes of the other set, each of said vanes comprising a metal envelope having sound deadening material disposed therein.

10. A residential air changer having a rotary impeller, a plurality of vanes in said impeller, each of said vanes constituting a pair of metal plates, said plates having a layer of sound deadening material therebetween, one of said plates having overfolded marginal flanges turned toward the opposite plate and arranged to space said plates apart to prevent said sound deadening layer from being compressed therebetween, and the opposite plate having a pair of marginal flanges overlapping the longitudinal side edges of

the adjacent plate to secure the plates together and having a pair of lateral flanges at opposite ends for securing the vane in the impeller.
